UNITED STATES PATENT OFFICE.

GUSTAVE L. HERZ, OF NEW YORK, N. Y.

SPARK-PLUG.

1,229,748.

Specification of Letters Patent. Patented June 12, 1917.

Application filed January 31, 1917. Serial No. 145,683.

To all whom it may concern:

Be it known that I, GUSTAVE L. HERZ, a citizen of the United States, and resident of the borough of Manhattan, in the city and State of New York, have invented a new and useful Improvement in Spark-Plugs, of which the following is a specification.

In spark plugs heretofore produced where the insulator was cast into the shell, it has been found practically impossible to maintain a gas-tight connection between the insulator and shell owing to the unequal expansion of the materials under the extreme variations of heat to which the plugs are exposed.

The object of my invention is to provide certain improvements in this type of spark plug whereby the insulator is not only interlocked to the shell but is also caused to have a gas-tight connection therewith, under all heat conditions. This object is obtained by providing the bore of the shell with one or more tapered portions in which the insulator is forced tightly under all conditions of temperature, by the pressure of the gases in the engine cylinder to which the spark plug is applied. In the present instance, I have shown the shell bore as having two tapered portions at different distances from the longitudinal axis of the spark plug, connected by a flaring portion.

A practical embodiment of my invention is represented in the accompanying drawings in which,

Figure 1 represents my improved spark plug in top plan,

Fig. 2 is a longitudinal central section through the same, and

Fig. 3 is a longitudinal central section through the shell.

The spark plug comprises the shell 1, the insulator 2, and the central electrode 3. The insulator 2 is composed of any suitable insulating material and is cast into the shell in the manufacture of the spark plug. The shell bore has, beginning at its inner end, respectively a cylindrical portion 4, a tapered portion 5, a flaring portion 6, and a second tapered portion 7, interlocked at the

outer end of the shell. The tapered portion 5 is shown as nearer to the longitudinal axis of the plug than the tapered portion 7. It will be seen that when pressure is applied to the insulator, it will tend to force the insulator outwardly, giving it a wedging action in the tapered portions 5 and 7 of the shell, thus insuring a gas-tight connection between the insulator and shell at these points, irrespective of the relative different expansions of the material of the insulator and shell. At the same time the insulator is interlocked to the shell.

It is evident that the form shown is only one of many different embodiments of my invention and hence I do not wish to limit myself to the particular embodiment herein shown and described, but

What I claim is:

1. A spark plug comprising a shell and an insulator cast therein, the shell bore having two tapered portions whereby the insulator has a gas-tight connection therewith because of its wedging action in the tapered portions, under pressure.

2. A spark plug comprising a shell and an insulator cast therein, the shell bore having two tapered portions connected by a flaring portion whereby the insulator is interlocked to the shell and has a gas-tight connection therewith because of its wedging action in the tapered portions, under pressure.

3. A spark plug comprising a shell and an insulator cast therein, the shell bore having two tapered portions at different distances from the longitudinal axis of the plug, whereby the insulator has a gas-tight connection therewith because of its wedging action in the tapered portions, under pressure.

4. A spark plug comprising a shell and an insulator cast therein, the shell bore having two tapered portions at different distances from the longitudinal axis of the plug, connected by a flaring portion, whereby the insulator is interlocked to the shell and has a gas-tight connection therewith because of its wedging action in the tapered portions, under pressure.

5. A spark plug comprising a shell and an insulator cast therein, the shell bore having successively, a cylindrical portion, a tapered portion, a flaring portion, and a second tapered portion, whereby the insulator is interlocked to the shell and has a gas-tight connection therewith because of its wedging

action in the tapered portions, under pressure.

In testimony, that I claim the foregoing 10 as my invention, I have signed my name this 25th day of January 1917.

GUSTAVE L. HERZ.
